UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

AUTOMATIC GOVERNOR.

Application filed November 5, 1925. Serial No. 67,120.

This invention relates to an automatic governor and as illustrated and described herein, it is particularly adapted for use, for controlling the time of ignition in an internal combustion engine.

It is well understood that the spark advance should be substantially coincident with the increase in the speed of the engine, and contrariwise should be decreased with a decrease in speed of the engine. It is practically impossible to get proper manual control of the ignition spark control.

My invention is therefore directed to improvements in automatic governors for ignition spark control.

In various devices of the prior art, with which I am familiar, it is the usual practice to pivot the weights or weighted arms at one end, such for example as illustrated in the Moore Patent, 1,388,743, issued August 23rd, 1921, but I have found that such an arrangement reduces the effective force of the weights, that is to say, those portions of the weights near the pivot points produce but little effect, as will be apparent from a study of such an arrangement.

Another objection which I have found to a structure similar to that shown in the said Moore patent, is that the ends of the weights, being some distance from the pivot points are apt to flop back and forth at low speed, striking the driven member, and thereby producing a noise.

A still further objection to a governor of the type disclosed in said Moore patent, is that it is not strictly interchangeable for different directions of rotation of the operating shaft, that is to say, if it is desired to rotate a governor of the Moore type opposite in direction from that first intended, the weights must be assembled in reverse position in order to get good operation.

One of the objects of my invention is to provide a governor for the purpose herein described, in which the weights are substantially equally balanced on a central median line, whereby the centrifugal force acts uniformly on all parts of the weight.

Another object of my invention is to provide a governor which will operate equally well in either direction of rotation, without shifting the position of any of the parts.

Another object of my invention is to provide a governor in which the friction is reduced to a minimum.

Another object of my invention is to provide an arrangement in which the link connections between the weights and the driven member are provided with bearings on both sides of the link, to insure long life of the pivot members.

A still further object of my invention is to provide means for eliminating or reducing to a minimum any noise produced by the weights at low rotative speeds of the governor.

These and other objects will be apparent to one skilled in this art, after a study of the specification taken in connection with the annexed drawing; wherein

Figure 1 is a plan view of the governor with the cover removed, and showing the parts in normal idle or retard position.

Figure 2 is a view similar to Figure 1 but with the parts moved to the full advanced position.

Figure 3 is a section on the line 3—3 of Figure 1 but with the cover in place.

Figure 4 is a view of a modified form of one of the elements included in one of the weight members.

Figure 5 is a view looking at the interior of the cover as removed from its cooperating member.

Figure 6 is a section through the heavier member on which the cover fits.

Figure 7 is a partial section or view on the line 7—7 of Figure 5.

Figure 8 is a plan view of the driven member removed from the casing.

Figure 9 is a section through the driven member taken through the lugs which carry the link pivots, and Figure 10 is a view of a nut which fits within the end of the driven member and engages the shaft of the ignition unit.

Referring now to the details, wherein like numbers refer to corresponding parts in the various views, 1, is a rigid member comprising a part of the driving member the other portion of said driving member being in the form of a cover 2, fitting on the flange 3 of the member 1, that has a hub 4, within which fits stem 5, of a driven member 6. The stem 5 is preferably tapered to receive the tapered end of the shaft of the ignition unit, such as a magneto. A nut 7 shown in Figure 10 being provided to fit within the bore 8 of the driven member 6, and being threaded at 9, to engage the threaded end of the

shaft of the ignition unit. A keyway 10, is provided in the stem 5, and as the end 11, of the nut 7, comes against the angular shoulder 12, driven member 6, is drawn into 5 firm engagement with the shaft of the ignition unit.

The member 1, is provided on its inner surface with flanges 13, which extend clear across the inner face thereof thereby forming 10 a groove or guideway 14.

Positioned across the flanges 13, and substantially symmetrically disposed with respect thereto are a pair of weights 15 and 16; these weights are preferably made up 15 of three punchings fastened together as by means of rivets 17. The middle lamination is cut away at its central portion, as indicated by the dotted line 18, to provide clearance for one end of link 19, which has a 20 pivot pin 20, preferably immovably fastened thereto, so that the ends of the pins have a bearing in the top and bottom pieces comprising the weights 15 and 16, all as clearly shown in Figure 3. The pivot pin 20, extends beyond the weight 15 into the groove 14, and carries a roller 21, thereon, which is likely to move up and down in the groove or guideway 14, in engagement with the sides of the flanges 13, as the weights 15 and 25 16 respond to centrifugal force. The middle lamination of weights 15 and 16 has extensions in the form of hooks 22, and these adjacent projections or hooks are engaged by springs 23, and 24, whereby the weights are 30 held in retard position as shown in Figure 1. The inner ends of the links 19, are provided with pivot pins 25, that are preferably immovably attached to the links, but the ends of the pivot pins 25, are movable in 35 the holes 26 of the lugs or ears 27, which extend from the driven member 6. In order to eliminate or reduce to a minimum any noise which the weights might produce on returning suddenly to retard position, I provide 40 the driven member with bumpers 28, of some suitable material, such as fibre or rawhide, on which the weights rest in retard position.

Since a complete housing for the driven member 6, is provided by the parts 1 and 2, a driving connection must be made to the casing, this is done through the medium of a plurality of studs 29, three being shown in Figure 5. The studs 29 are fastened to the 45 cover in any satisfactory manner. Likewise the cover is held to the rigid member 1, by a pair of studs 30, which pass through the holes 31, as will be seen from Figures 5, and 6, and 7. It is to be understood that a suitable coupling member is adapted to engage the studs 29, to drive the governor and the ignition shaft.

The governor so far described will produce substantially a straight line curve, but 50 for certain requirements this straight line

curve requires to be modified and this modification can be brought about, by the use of an auxiliary spring associated with the weights. For this purpose I prefer to use a flat spring 32, which may be attached to the weights in any satisfactory manner, that shown in the drawing comprises a flat surface in the outer part of the weights on which the flat spring 32, rests; the springs are held in position by peening over the metal as shown in Figure 3. It will be understood that the springs 32 are of suitable thickness and quality to give the desired modification to the spark advance curve as the ends of the springs 32 engage the inner wall of the rim or cover 2, when the weights move away from the center.

In place of the hooks shown in Figures 1, and 2, the central lamination of the weights may be constructed with eyelets 33, as shown 55 in Figure 4.

The operation of my device will be apparent without any extended description thereof, but it may be pointed out, that the weights are so positioned over the narrow flanges 13, as to produce little friction, and the weights are so disposed as to be acted on uniformly by centrifugal force and consequently they move in a lateral direction from the driven member, being guided by the rollers 21, operating in the guideway 14. As the weights 15 and 16 move outwardly toward the rim of the cover 22, under the action of centrifugal force the driven member 6, is shifted in position or advanced so as to advance the time of the spark produced in the engine cylinders. The auxiliary spring 32 as has been pointed out, is arranged of suitable thickness and length and material as to modify the speed of rotation 100 of the given member as desired, to produce the necessary spark curve.

It will also be apparent that the governor can be operated in either direction of rotation without any change in position of the weights or their associated members. Furthermore the pivot pins associated with the links being fastened rigidly to the links and having bearings on both sides of the links, gives a structure insuring long service for these parts.

It will be apparent that various changes may be made in the details comprising the governor herein described and I therefore do not wish to be unduly limited in the interpretation of the appended claims.

Having thus described my invention what I claim is:

1. In a device of the character described, the combination of a multi-part driving member and a driven member, said driven member being housed within the driving member, studs on one of the parts of said driving member provided with means to bind the said parts together, a guideway 125

extending across the inner face of one of the parts of said driving member, weights positioned over at least a portion of said guideway on both sides of the driven member; links connecting said weights to the driven member, resilient means connecting adjacent ends of said weights and means associated with said weights and operating in said guideway to cause said weights to move laterally with respect to the driven member.

2. In a device of the class described, a driving member comprising; a relatively rigid member having an outwardly projecting central hub and a cover member fitting on the outer part of said rigid member, means for holding the cover to the rigid member and means for making driving connections to said driving member; a driven member positioned by the hub and housed within the cover, weights symmetrically disposed on diametrically opposite sides of the driven member, springs connecting adjacent ends of said weights, links joining the driven member to diametrically opposite points on the weights and on a median line thereof coinciding with a diameter through the weights and means associated with the weights and said rigid member for guiding the weights in a lateral direction with respect to the driven member as the weights respond to centrifugal force.

3. In a device of the class described, a driving member and a driven member, said driving member comprising a member having a hub and a cover member, said driven member being carried by said hub member, said hub member having a pair of flanges across its inner face forming a guideway, weights disposed on opposite sides of the driven member and resting on said flanges, links connecting said driven member to the weights on a median line therethrough, springs connecting adjacent ends of the weights and friction reducing members in the guideway cooperating with the weights to guide them as they move under the action of centrifugal force.

4. In a device of the character described, a driving member, a driven member housed within the driving member and mechanism for coupling said members together including centrifugal means for shifting the driven member about its axis relative to the driving member as the speed of the driving member varies, and springs connecting adjacent ends of the centrifugal means, said coupling mechanism, including links connected at one end to the weights so as to allow them to move laterally away from each other and an auxiliary spring member carried by at least one of the centrifugal means and acting at both ends at a predetermined time for modifying the effect of said springs as and for the purpose described.

5. In a governing device, a driving member consisting of two parts joined together at their periphery and having central openings with means for holding said parts in operative position, a driven member having ears thereon positioned within said two parts and having a hub positioned in the central opening of one part of the driving member and means for coupling said members together including slidably mounted laminated weights with links having pins at each end fixed therein and pivoted at one end between the outer of said laminations and pivoted at the other end between said ears on the driven member, springs connecting adjacent ends of the weights and means mounted on one end of said link pins and cooperating with a part of the driving member for guiding said weights in their movements when responding to centrifugal force.

6. In a governing device, a driving member consisting of two parts joined together at their periphery and having central openings with means for holding said parts in operative position, a driven member having ears thereon positioned within said two parts and having a hub positioned in the central opening of one part of the driving member and means for coupling said members together including slidably mounted laminated weights with links having pins at each end fixed therein and pivoted at one end between the outer of said laminations and pivoted at the other end between said ears on the driven member, springs connecting adjacent ends of the weights, flanges across the inner face of said hub part forming a guideway and rollers mounted on one end of said link pins within said guideway for the purpose described.

7. In a device of the class described, a driving member comprising a casing of two parts with means for holding said parts together, a driven member housed within and rotatably supported by the casing a pair of weights slidably supported in substantially parallel relationship on a part of the casing, means for resiliently connecting said weights together at their adjacent ends and link means connecting said weights on a median line therethrough to the driven member so said weights in moving will tend to move in parallel relationship, means cooperating between the weights and a part of the driven member to assist in maintaining said parallel relationship, and resilient means carried by the weights and extending in a tangent position thereto toward two opposite points of the casing and adapted to engage the casing at a predetermined speed of rotation of the governor for the purpose described.

In testimony whereof, I affix my signature.

EDWARD B. NOWOSIELSKI.
